UNITED STATES PATENT OFFICE.

W. CLAY LUTZ, OF BEDFORD, ASSIGNOR OF ONE-HALF TO JOHN DU BOIS,
OF EVERETT, PENNSYLVANIA.

FIRE-ESCAPE.

SPECIFICATION forming part of Letters Patent No. 290,080, dated December 11, 1883.

Application filed October 8, 1883. (No model.)

To all whom it may concern:

Be it known that I, W. CLAY LUTZ, a citizen of the United States of America, residing at Bedford, in the county of Bedford and State 5 of Pennsylvania, have invented certain new and useful Improvements in Fire-Escapes, of which the following is a specification, reference being had therein to the accompanying drawings.

10 My invention relates to an improvement in portable fire-escapes; and it consists in the sill-clutch A, having hinged platform B, clamp A' for standards B' and B², pulleys C and C', rope E, snap-hook F, ring G, stirrup H, and 15 in the combination and arrangement of the parts, substantially as hereinafter more fully described.

In the drawings, Figure 1 is a side elevation, and Figs. 2, 3, and 4 are detail views.

20 The object of my invention is to produce a portable fire-escape which may be packed into little space, and thus be readily conveyed as baggage from place to place, as a means of rendering the traveling public independent of 25 the usually stationary fire-escapes. In its construction I employ the platform-clutch A, represented in Fig. 1 as resting on the window-sill, (where it is located in practice,) to which is hinged the clamp A', which projects 30 over the inner side of the window and holds the platform rigidly in position.

The standards B' and B² are cast integral or otherwise rigidly secured to the platform-clutch A, and have secured thereto the two 35 pulleys C and pulley C'. The rope E is passed over pulley C', and is then crossed and con-

veyed by the pulleys C, and in continuation it is coiled around ring G. It is spliced at one end to the stirrup H, the other end thereof being held by the hand of the person descending. The snap-hook F is secured to ring G by means of the spliced rope E'. When in use, the points of the platform-clutch A are pressed into the sill and the clamp A' fastened or hooked beneath the inner side of the sill, 4 and the rope is then adjusted under the arms of the person descending, the ring G preventing the rope which is coiled thereon from too tightly compressing the body of the person descending. The stirrup H is held in eyes e', 5 provided at the ends of the semicircular ring H', which ring is spliced to the rope, as shown.

Having thus fully described my invention, 5 which I claim, and desire to secure by Letters Patent, is—

1. A portable fire-escape consisting of a sill-clutch and clamp for securing it to a window-sill, a rope suspended on pulleys, having secured thereto a stirrup, and an adjustable ring having spliced thereto a snap-hook, substantially as shown and described.

2. The combination of the sill-clutch A, clamp A', standards B' and B² for pulleys C and C', and rope E, having secured thereto body-inclasping mechanism, substantially as shown and described.

In testimony whereof I affix my signature in presence of two witnesses.

W. CLAY LUTZ.
